UNITED STATES PATENT OFFICE.

WILLIAM THOMAS REED, OF WINNIPEG, MANITOBA, CANADA.

SPARK-ARRESTER.

SPECIFICATION forming part of Letters Patent No. 352,353, dated November 9, 1886.

Application filed April 2, 1886. Serial No. 197,561. (No model.)

To all whom it may concern:

Be it known that I, WILLIAM THOMAS REED, of the city of Winnipeg, in the county of Selkirk, in the Province of Manitoba, Canada, 5 mechanical engineer, have invented an Improved Spark-Arrester, of which the following is a specification.

The device is more particularly adapted for locomotive-boilers; and the object of the invention is to arrange a device within the smoke-box of the boiler which will arrest the sparks and effectually grind them to a fine powder before they are discharged through the smoke-stack; and it consists, essentially, in placing 15 a corrugated deflecting-plate set at an angle in front of the tubes, so that the sparks escaping from them will strike against the corrugated plate and be directed against a corrugated base-plate, at the end of which a curved corrugated plate is placed, which latter plates constitute additional grinding-surfaces for the purpose of grinding to a powder the sparks which first strike the corrugated deflecting-plate, substantially as hereinafter specified.

25 Figure 1 is a longitudinal section of the smoke-box in perspective. Fig. 2 is a detail showing the manner of securing the deflecting-plate.

A is the tube-sheet.

30 B is the steam-pipe leading to the cylinders. C are the tubes, and D the exhaust-nozzle.

E is a coarse wire-netting extending across the smoke-box immediately below the exhaust-nozzle D.

35 F is a corrugated deflecting-plate, preferably corrugated on both sides, and set at an angle, as indicated, immediately in front of the tubes C. This deflecting-plate F rests upon an angle-iron, G, riveted to the smoke-box, and is 40 supported thereon by a series of studs, a, screwed into the angle-iron G, each stud being preferably provided with a cotter-pin, which, when inserted in the slot made in the stud a, holds the plate F in position, while it permits

45 the plate F to be readily removed when it becomes necessary to clean the tubes C. I may mention here that the plate F may be made

in sections so as to facilitate its removal, each section being provided with a handle, b.

H is a corrugated base-plate extending from 50 the tube-sheet A to the door I of the smoke-box. I prefer to set this plate H on an incline, as indicated, for when so set the best results are secured.

K is a corrugated plate, preferably curved, 55 as indicated, and connected to the smoke-box door I.

The effect of the corrugated plates arranged as shown and described is as follows: The sparks as they escape from the ends of the 60 tubes strike against the corrugated plate F, which deflects them toward the base-plate H. The draft produced by the exhaust-steam from the nozzle D draws the sparks along the corrugated base-plate H till they strike the corrugated plate K, thence up along its curved 65 surface and against the netting E, through which only sparks so small as to do no harm can escape, the larger pieces being whirled around the smoke-box against the corrugated 70 surfaces of the plates mentioned until they are ground so fine as to do no harm when they escape from the smoke-stack. The corrugated surfaces of the plates F, H, and K are preferably chilled in order to increase their 75 durability.

What I claim as my invention is—

1. The corrugated deflecting-plate F, in combination with the corrugated base-plate H and corrugated plate K, arranged substantially as and for the purpose specified.

2. The corrugated deflecting-plate F, in combination with the corrugated base-plate H, corrugated plate K, and netting E, arranged substantially as and for the purpose specified. 85

3. The corrugated deflecting-plate F, supported on the angle-iron G by the studs a, substantially as and for the purpose specified.

Toronto, March 20, 1886.

W. TH. REED.

In presence of—

CHARLES C. BALDWIN,
CHAS. H. RICHE.
